UNITED STATES PATENT OFFICE.

ALVIN M. MASON, OF BOZEMAN, MONTANA.

THRESHING-MACHINE CYLINDER.

1,302,574.

Specification of Letters Patent.

Patented May 6, 1919.

Application filed April 8, 1918. Serial No. 227,312.

To all whom it may concern:

Be it known that I, ALVIN M. MASON, a citizen of the United States, residing at Bozeman, in the county of Gallatin and 5 State of Montana, have invented certain new and useful Improvements in Threshing-Machine Cylinders, of which the following is a specification.

The invention relates to improvements in 10 threshing machine cylinders, and more particularly to means for fixedly securing or locking the toothed cylinder bars to the opposite heads of the cylinder to insure against side and rotary movement or other displacement of the bars and to maintain the same in proper rigid relation to the cylinder.

The broad object in view is the provision 20 of improved means of the foregoing character embodying novel features of construction, comprising a minimum of parts with consequent simplicity, possessing the utmost strength and rigidity, and allowing for independent removal and replacement of the cylinder bars with ease and facility.

25 The invention further resides in the novel construction, arrangement, and combination of parts as will be hereinafter fully pointed out and described in connection with the accompanying drawings, in which—

30 Figure 1 is a view in elevation of a fragment of a cross-bar annular cylinder encircling supporting member, the supporting member being shown as provided with a socket in which is mounted or inserted in 35 locked relation a flanged bar-lock member adapted to secure the cross-bar in proper relation to the cylinder, the cross-bar being indicated sectionally.

Fig. 2 is a top plan view of the elements 40 of Fig. 1.

Fig. 3 is a fragmental perspective view of a cross-bar provided with the bar securing device of my invention.

Fig. 4 is a fragmental perspective view 45 of the aforementioned cross-bar supporting member provided with the bar lock receiving socket of the invention.

Referring more specifically to the drawings, the numeral 1 designates an annular 50 cross-bar supporting member which usually embraces the opposite heads of the cylinder of a threshing machine, the same being fixedly secured to said heads. In carrying out my invention I provide said bar supporting member with the required number 55 of transverse slots such as illustrated.

Each slot comprises a circular curved face portion 2 beginning at one edge of the slot and extending to a point where the curved face is interrupted by a flat faced abutment 60 or stop 3 which abutment or stop extends from the opposite edge of the slot to the point where it meets the curved portion 2. The opposite side edges of the curved face portion 2 of the socket are chamfered or 65 beveled off as at 4, the bevels extending from the upper face of the supporting member 1 where the scope of the bevels is deepest and gradually merging with the side faces of the supporting member. 70

The cross-bars of the cylinder which carry the bar teeth 5 are formed with the integral securing members adapted to be fitted tightly in the aforementioned sockets. Each securing member is substantially an enlargement projecting right angularly from the bar and consisting of a circularly curved face 6 extending from one edge of the flat top face of the cross-bar to a point where the curve meets a flattened off face 7 of a 80 cuneate groove 8 extending through the thickness of the cross-bar and oppositely thereof to the curved face 6. A pair of curvilinear flanges 8 are spaced apart by the face 6 and project outwardly, said flanges 85 diverging from one another and gradually curving to merge with the face 6. When the lock-member is fitted into the slot by a rotary movement the flanges will engage in wedge fashion with the tapered beveled off 90 portions 4, rotary movement being limited and the locking member confined in the slot by engagement of the stop 3 with the flat face 7 of the slot. In accomplishing the removal and replacement of the bars the 95 outstanding bar teeth 5 may be utilized as a leverage means.

Having described my invention, I claim:—

1. A device of the character described 100 consisting of a supporting member provided with a transverse slot or recess, said slot or recess being formed with a circularly curved face extending from one upper edge of the slot and terminating at a point where the same meets the flat face of 105 an abutment or stop, the latter extending inwardly from the remaining upper edge of the slot, beveled off portions at opposite sides of said curved face said portions extending from the upper face of the supporting 110 member and gradually tapering to merge with the side faces of the supporting

member; and a bar locking member formed and proportioned to fit said slot and engage said beveled off portions, said member having a circularly curved face adapted to engage the curved face of the slot, a cuneate groove having a flat face adapted to engage the stop of the slot, and a pair of curvilinear flanges spaced apart by the curved face of the locking member, said flanges diverging from one another and gradually curving to merge with the latter

curved face and being adapted to engage the beveled off portions of the supporting member.

2. A tooth bar having a rounded face and 15 spaced locking flanges forming friction members and said rounded face terminating in a flat abutment face opposite the friction members.

In testimony whereof I affix my signature. 20

ALVIN M. MASON.
